UNITED STATES PATENT OFFICE

154,588

DESIGN FOR A VESSEL HOLDER

James M. Collins, San Fernando, Calif.

Application October 20, 1947, Serial No. 142,010

Term of patent 14 years

(Cl. D44—29)

To all whom it may concern:

Be it known that I, James M. Collins, a citizen of the United States, residing at San Fernando, county of Los Angeles, State of California, have invented a new, original, and ornamental Design for a Vessel Holder, of which the following is a specification, reference being had to the accompanying drawings, forming a part thereof.

Figure 1 is a perspective elevation of a vessel holder embodying the present invention.

Figure 2 is a side elevation of the device shown in Figure 1.

Figure 3 is a plan view of the device shown in Figure 1.

The broken line disclosure of a can in Figure 1 is for illustrative purposes only.

I claim:

The ornamental design for a vessel holder, substantially as shown and described.

JAMES M. COLLINS.
